CURVED-LINE SCRIBER.

1,299,006.

Specification of Letters Patent.

Patented Apr. 1, 1919.

Application filed September 6, 1918. Serial No. 252,907.

To all whom it may concern:

Be it known that I, THEODOR MÜLLER, a citizen of the Republic of Switzerland, residing at No. 203 Forchstrasse, Zurich, Switzerland, have invented certain new and useful Improvements in Curved-Line Scribers; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

15 This invention relates to curved-line scribers or compasses comprising two guide-rails and a bar which is provided with a holder for a pencil or the like, and which cooperates with two slide-blocks mounted in 20 said guide-rails.

In known curved-line scribers of this kind, the guide-rails are arranged at right angles and rigidly connected. Such compasses are only adapted for describing ellipses.

25 The invention consists in providing on a scriber or compass comprising in contradistinction to the scribers referred to a guide-rail pivotally mounted on the other one, so that it can be adjusted to the right and left 30 with regard to the middle position assumed by the guide-rails when they are set at right angles to each other, means for fixing automatically said pivotally mounted rail in the different positions into which it is brought.

35 Such a scriber may be used, when the two rails are set at right angles to each other, for describing elliptical curves cutting determinate axes at right angles, while in an inclined position of the rails with regard to 40 each other it may be used for describing curves which appear with regard to the same axes as lines curved to a greater degree and which may be regarded approximately as a compound line.

45 The invention also consists in the construction and combination of parts and details, which will be fully described hereinafter, and finally pointed out in the claims.

This invention will now be more particularly described with reference to the accompanying drawing, which illustrates two constructional examples of the invention.

In this drawing:

Figure 1 is a front view of the first embodiment of the invention;

Fig. 2 is a cross-section on the line II-II of Fig. 1;

Fig. 3 is a plan view corresponding to Fig. 1, partly in section;

Fig. 4 is a cross-section on the line IV-IV 60 of Fig. 3;

Fig. 5 shows on an enlarged scale a detail of Fig. 3;

Fig. 6 shows a front view of a part of the curved-line scriber used as beam-compass, 65

Fig. 7 is a corresponding bottom view of said part.

Fig. 8 illustrates a detail on an enlarged scale, and

Fig. 9 shows parts of curved-lines de- 70 scribed by means of the new compass.

Fig. 10 is an end view of a part of the second embodiment of the invention, and

Fig. 11 shows a horizontal section of said part. 75

1 and 1' denote two guide-rails each provided with a longitudinal groove 2 and 2' respectively. 3 is a lower part arranged at right angles to the guide-rail 1 and rigidly connected to the latter. The lower part 3 80 acts as a support for the guide rail 1'. The latter is provided at one end with a guide 4 fixed to the bottom of the groove 2' and projecting beyond said end, so that the guide-rail 1' can be pivotally connected to the 85 guide-rail 1 by means of said guide 4. 5 (Figs. 3 and 5) is the axis about which the guide-rail 1' is adapted to pivot. 4' are two guide-ledges arranged in recesses of the side-walls of the groove 2' and fixed to said walls 90 (Figs. 3 and 5). The ends of the guide-ledges 4' extend into a recess of the guide-rail 1, which recess is so shaped, that the ends of the guide-ledges 4 come to rest in the two outermost positions of the adjustable guide-rails against the oblique lateral walls of said recess of the guide 1. The guide-ledges 4' provide in all positions of the guide-rail 1' for a smooth going over of the groove 2' into the groove 2. 6 denotes 95 a line-scale provided on the lower part 3 for adjusting the guide-rail 1' in an exact manner. 7 denotes a bar having a slot 8. Two slide-pieces 9 and 10 mounted in the guide-grooves 2 and 2' respectively are adapted to be adjusted in said slot 8 and to be secured to the bar 7 in determinate positions by means of wing-nuts 11 and 12 respectively. 13 (Fig. 3) is a block movably mounted in the bar 7 and provided with a millimeter-scale. 110

110

To the block 13 is secured a holder 14 carrying a pencil 15. 16 is a set-screw which is for securing the block 13 in the required position. 17 denotes fixing points; the latter are arranged in the middle line of the guide-rail 1 on the bottom side of the latter. Each of said points 17 is formed integral with a screw-threaded pin 17². The latter is adapted to be secured into a metallic sleeve 17¹ inserted into a recess of the rail 1. Owing to this construction, it is thus possible to remove the fixing points 17 when the compass has to be placed upon a base into which said points cannot be inserted, as for instance on a glass-plate. In the latter case, a suitable material preventing a sliding of the compass on the smooth base such as putty, may be inserted into the spaces previously taken up by the pins 17².
20 23. (Figs. 3 and 4) is a metallic stopping or securing member provided with rounded off notches 24. This member is fixed to the lower part 3 by means of screws 26 (Fig. 4). The shape of the stopping member 23 is adapted to the arc described by the free end of the guide-rail 1' when it is turned about the pivot 5. 27 denotes a hole provided in the rail 1 near its end below the guide-groove 2'. Within the hole 27 is 30 movably mounted a pin 29 having a rounded off head and acted upon by a spring 28. The recesses 24 of the stopping member 23 are arranged in one line. Upon an adjustment of the guide-rail 1', the pin 29 comes to lie opposite a notch 24, it being then pressed into the latter by the spring 28, thus securing the rail 1' in the position into which it has been adjusted. The rounded off shape of the head of the pin 29 and of the notches 24 provide for an easy coming out of engagement of the pin 29 with said notches when a lateral pressure is exerted upon the guide-rail 1'. The three recesses 24 provided on each side of the central notch 30, which latter corresponds to the position of the guide rail 1' in which it is at right angles to the rail 1, are arranged in a symmetric manner with regard to said notch 30, so that the adjustments obtained correspond 40 to those obtained by means of the mark-lines 1, 2, 3 of Fig. 3. The turned up ends 25 of the member 23 are for limiting the lateral movement of the guide-rail 1'.
50 When it is intended to describe with the compass hereinbefore described an ellipse cutting at right angles a coördinate system, the guide-rails 1, 1', the directions of which determine said coördinate system, are at first set at right angles with regard to each other; 55 hereupon the slide-pieces 9, 10 are adjusted in accordance with the major and minor axis of the ellipse to be drawn, the compass being secured in the proper place on the surface on which the ellipse has to be described by 60 means of the points 17. When all this has

been effected, a lateral pressure is exerted upon the end of the bar 7 carrying the pencil-holder 14, so that the pencil 15 describes then one half of the ellipse 18 (Fig. 9), the slide-pieces 9 and 10 being guided thereby in 70 a positive manner in the grooves 2 and 2' respectively. The other analogous half of the ellipse may be drawn as soon as the scribe has been turned about an angle of 180°. When the guide-rail 1' has been 75 moved into an inclined position, other elliptical curves may be drawn. By adjusting for instance, the rail 1' in such a manner, that the pin 29 is caused to engage into the outermost left notch 24, in which case the 80 right hand edge of the guide rail 1' coincides with the mark line 3 of the scale 6 provided on the lower part, the elliptical curve 19 (Fig. 9) may be drawn. The latter is curved to a greater degree than the curve 18 with 85 regard to the same system of coördinates. This is, however, only approximately true, as the curve 19 does not pass exactly through the ends of the axes of the elliptical curve 18; but the difference is so small—always 90 assumed that the guide-rail 1' is not moved too much from its middle position—that this is of no practical importance. The curved line 19 may be regarded with sufficient great approximation as one half (the left hand 95 one) of a compound curve. For the purpose of describing the analogous second half, the guide-rail 1' is adjusted in such a manner, that the pin 29 is caused to engage into the outermost right notch 24, the left hand 100 side edge of the rail 1' coinciding in this case with the other mark-line 3. In order to describe a closed curve, the compass has to be turned about an angle of 180° when one half of the curve has been described; 105 when this has been done, the other half can be drawn.

A part of the compass shown may also be used as beam-compass (Figs. 6 and 7). To this end the bar 7 and the slide-pieces 9, 110 10 are removed from the guide-rails. Preferably one of the slide-pieces is also removed from the bar 7 and to the slide-piece remaining on the bar 7 is secured a cap 21 provided with a fixing point 20 by means of a screw-threaded extension 22 (Fig. 8). Such a beam-compass can be used for drawing circles, the required adjustment being effected by an adjustment of the bar 7 relatively to the fixing point 20, or by an adjustment of 115 the block 13 movably mounted in the bar 7.

In the second embodiment of the invention shown in Figs. 10 and 11 the parts not shown correspond to the corresponding parts of the first construction.

The arc shaped metallic stopping member 23 shown in Figs. 10 and 11 and fixed to the lower part 3 is provided with a series of holes 31 which are connected by means of slots 32. Each hole 31 is partly of cylindri- 130

cal and partly of conical shape. The cylindrical part of each hole 31 is situated on that side of the member 23 which lies opposite the guide-rail 1'. The pin 29 acted upon by 5 a pressure-spring 28 is movably mounted within a sleeve inserted into the bore 27. The pin 29 has a conical part 34 and it comprises between said part 34 and a semi-spherical head 35 a cylindrical part 33 of 10 smaller diameter. The diameter of the part 33 corresponds to that of the slots 32, while the diameter of the head 35 corresponds to that of the holes 31.

The adjustment of the guide-rail 1' takes 15 place in the following manner: A pressure is exerted upon the head 35 of the pin 29 until the conical part 34 comes out of engagement with the corresponding conical part of the hole 31, so that the part 33 of smaller 20 diameter can then be pushed into the corresponding hole 32 and the rail 1' adjusted to the desired amount to the right or left respectively. As soon as the rail 1' has been set into the proper position, the head 35 is 25 released. The spring 28 presses then the pin 29 outward, so that the conical part 34 is caused to engage the conical part of the hole 31. In consequence of this, the rail 1' is secured in the position into which it has 30 been adjusted.

What I claim now as my invention is:

1. A curved-line scribe, comprising a guide-rail having a guide-groove, a second guide-rail also provided with a guide-groove 35 and pivotally connected in such a manner to said first mentioned guide-rail that it is adapted to be adjusted with regard to the middle position assumed by it when the two rails are set at right angles with regard to 40 each other to the right or left respectively, two slide-pieces each of them being mounted in a guide-groove of one of said guide-rails, a bar provided with a slot, said slide-pieces being adapted to be adjusted in said slot, 45 means for fixing the slide-pieces in the slot of said bar, means for securing a pencil on the bar and securing or stopping means carried partly by the pivotally mounted guide-rail and partly by the other guide-rail for 50 securing a proper adjustment of the pivotally mounted guide-rail as well in the position of the two rails in which they are set at right angles with regard to each other as in the position in which the pivotally mounted 55 guide-rail is set into an inclined position with regard to the other guide-rail.

2. A curved-line scribe, comprising a guide-rail having a guide-groove, a member arranged at right angles to said rail and rigidly connected thereto and provided with a line-scale, a second guide-rail also provided with a guide-groove resting on said member and pivotally connected in such a manner to the first mentioned guide-rail that it is 60 adapted to be adjusted with regard to the

middle position assumed by it when the two rails are set at right angles with regard to each other to the right or left respectively, two slide-pieces each of them being mounted in a guide-groove of one of said guide-rails, 70 a bar provided with a slot, said slide-pieces being adapted to be adjusted in said slot, means for fixing the slide-pieces in the slot of said bar, means for securing a pencil on the bar, a securing or stopping member fixed to 75 said member supporting the pivotally mounted guide-rail and an adjustable member mounted in the last mentioned guide-rail securing in connection with said supporting member a proper adjustment of the pivotally 80 mounted guide-rail as well in the position of the two rails in which they are set at right angles with regard to each other as in the position in which the pivotally mounted guide-rail is set into an inclined position 85 with regard to the other guide-rail.

3. A curved-line scribe, comprising a guide-rail having a guide-groove, a member arranged at right angles to said rail and rigidly connected thereto and provided with a line-scale, a second guide-rail also provided with a guide-groove resting on said member and pivotally connected in such a manner to the first mentioned guide-rail that it is adapted to be adjusted with regard to 90 the middle position assumed by it when the two rails are set at right angles with regard to each other to the right or left respectively, two slide-pieces, each of them being mounted in a guide-groove of one of said 95 guide-rails, a bar provided with a slot, said slide-pieces being adapted to be adjusted in said slot, means for fixing the slide-pieces in the slot of said bar, means for securing a pencil on the bar, a securing or stopping member fixed to said member supporting the pivotally mounted guide-rail and comprising 100 a part shaped in accordance with the arc described by the free end of the adjustable guide-rail when the latter is adjusted and 105 having a series of holes connected by slots, a pin movably mounted in the free end of the pivotally mounted guide-rail, said pin being provided at the end of the guide-rail with a thin portion corresponding to the 110 width of the slot and a thick portion adapted to fit into said holes and a spring also mounted in the free end of the pivotally mounted rail and acting upon the pin.

4. A curved-line scribe, comprising a 115 guide-rail having a guide-groove, a member arranged at right angles to said rail and rigidly connected thereto and provided with a line-scale, a second guide-rail also provided with a guide-groove resting on said member, a guide fixed to the bottom of the last mentioned guide-groove projecting beyond the end of the second guide-rail and pivotally connecting the latter to the first mentioned guide-rail, so that the second 120

- 4
- guide-rail is adapted to be adjusted with regard to the middle position assumed by it when the two rails are set at right angles with regard to each to the right or left respectively, two guide ledges mounted in recesses provided in the lateral walls of the guide-groove of the pivotally mounted guide-rail and fixed to said walls, the ends of said ledges extending into a recess of the 5 first mentioned guide-rail and being thus adapted to provide in all positions of the adjustable guide-rail for a smooth going over of the guide-groove of the latter into the guide-groove of the first mentioned 10 guide-rail, two slide-pieces, each of them being mounted in a guide-groove of one of said guide-rails, a bar provided with a slot, said slide-pieces being adapted to be adjusted in said slot, means for fixing the slide- 15 pieces in the slot of said bar, means for securing a pencil on the bar and securing or stopping means carried partly by the pivotally mounted guide-rail and partly by the other guide-rail for securing a proper ad- 20 justment of the pivotally mounted guide-rail as well in the position of the two rails in which they are set at right angles with re- 25 gard to each other as in the position in which the pivotally mounted guide-rail is 30 set into an inclined position with regard to the other guide-rail.
5. A curved-line scribe, comprising a guide-rail having a guide-groove, sleeves inserted into the lower part of said rail, fixing points removably screwed into said sleeves 35 and arranged in the middle line of the rail on the bottom side of the latter, a second 40 guide-rail also provided with a guide-groove and pivotally connected in such a manner to said first mentioned guide-rail that it is 45 adapted to be adjusted with regard to the middle position assumed by it when the two rails are set at right angles with regard to each other to the right or left respectively, two slide-pieces each of them being mounted 50 in a guide-groove of one of said guide-rails, a bar provided with a slot, said slide-pieces being adapted to be adjusted in said slot, means for fixing the slide-pieces in the slot of said bar, means for securing a pencil on 55 the bar and securing or stopping means carried partly by the pivotally mounted guide-rail for securing a proper adjustment of the pivotally mounted guide-rail as well in the position of the two rails in which they are 60 set at right angles with regard to each other as in the position in which the pivotally mounted guide-rail is set into an inclined position with regard to the other guide-rail.

In testimony that I claim the foregoing as my invention, I have signed my name.

THEODOR MÜLLER.
